UNITED STATES PATENT OFFICE.

LEONARD SATCHWELL, OF SLOUGH, ENGLAND, ASSIGNOR TO JOHN BRIGHTWEN ALEXANDER, OF BRIXTON, ENGLAND.

ELECTRIC FURNACE.

Application filed August 8, 1925, Serial No. 49,071, and in Great Britain October 21, 1924.

This invention relates to improvements in furnaces or chambers heated by the electric resistance method and has for its object to provide an improved construction of such 5 chambers or furnaces.

In accordance with the invention the furnace is constructed to accommodate a cylindrical drum or container adapted to contain the articles or material to be heated and bearing on rotatable shafts which extend outside the furnace, such shafts being connected together for rotation whereby to rotate the drum or container.

The invention is illustrated by way of example in the accompanying drawings. Figs. 1 and 2 are longitudinal and transverse sections respectively of a heating chamber constructed in accordance with the invention.

20 In the drawings the same reference characters indicate like parts.

Referring to the drawings, *c* is the heating element of the furnace or chamber, which is in the form of a split tube connected by leads *e* with the secondary *b* of a transformer, of which *a* denotes the core. *d* indicates a lagging of low thermal conductivity. The primary coil of the transformer may be suitable for an ordinary supply voltage and the ratio of transformation may be such as is suitable for providing heating currents of large value for the heating elements. The leads *e* which also can be conveniently arranged to act as supports should be of low 35 resistance value in comparison with the heating element *c*. *d'* represents the outer casing of the furnace.

The furnace is constructed to accommodate a cylindrical drum *h* adapted to contain the articles or material to be heated, and bearing upon rotatable shafts *f* which are mounted on bearings *g* and which extend within, and protrude a considerable distance beyond, the furnace, said shafts *f* being mechanically connected together by means of sprockets *i* and a chain *k*. As will be understood, when the shafts *f* are rotated

by hand or by an electric drive, the drum *h* is rotated by friction from the shafts *f*.

The portions of the shafts *f* which protrude from the furnace may serve as guides for the drum *h* in introducing it into the furnace, thereby insuring alignment of the drum *h* with the single turn coil heating elements *c*. In order further to facilitate entry and withdrawal of the drum *h* the whole structure (furnace, shafts and transformer) may be arranged to rock on a central point so that, when it is desired to cause the drum to enter the furnace, the whole 55 structure may be tilted so that the drum will move into its heating position along the shafts when they are rotated, and, in order to withdraw the drum after completion of the process, the structure may be tilted in the 60 opposite direction so that the drum will move outwards by gravity when the shafts are rotated.

When the drum is being heated, the shafts may be occasionally rotated to insure uniform distribution of heat throughout the drum or to insure contact, for example, of the articles to be sherardized with zinc dust.

The drum or container or/and material forms a secondary of another transformer, 75 of which the lining of the furnace constitutes the primary. The outer casing of the furnace may, if desired, be of iron of such proportions as will reduce the reluctance of the magnetic circuit of which the container 80 forms a part.

I claim:—

An electric furnace including a container for the material to be heated, said container enclosed by a split tube constituting a single 85 turn conductor, providing a circumferential path for the current, and rotary shafts freely supporting said container between them, substantially as and for the purpose described. 90

In testimony whereof I have signed my name to this specification.

LEONARD SATCHWELL.
